US00D914500S

(12) **United States Design Patent** (10) **Patent No.:** **US D914,500 S**
(45) **Date of Patent:** **** Mar. 30, 2021**

(54) **ACCESS-RESISTANT JAR**

(71) Applicant: **POLLEN GEAR LLC**, Hermosa Beach, CA (US)

(72) Inventors: **Shane Grant Blomberg**, Hermosa Beach, CA (US); **Edward Kilduff**, Hermosa Beach, CA (US)

(73) Assignee: **POLLEN GEAR LLC**, Hermosa Beach, CA (US)

(**) Term: **15 Years**

(21) Appl. No.: **29/685,913**

(22) Filed: **Apr. 1, 2019**

Related U.S. Application Data

(63) Continuation of application No. 29/670,346, filed on Nov. 15, 2018, which is a continuation-in-part of application No. 29/589,016, filed on Dec. 27, 2016, now Pat. No. Des. 842,700, which is a continuation-in-part of application No. 29/580,322, filed on Oct. 7, 2016, now abandoned.

CLAIM

The ornamental design for an access-resistant jar, as shown and described.

DESCRIPTION

FIG. 1 is a top perspective view of an access-resistant jar in an open condition in accordance with the present teachings. FIG. 2 is a bottom perspective view of the access-resistant jar of FIG. 1.

FIG. 3 is a first side view of the access-resistant jar of FIG. 1.

FIG. 4 is a second side view of the access-resistant jar of FIG. 11.

FIG. 5 is a third side view of the access-resistant jar of FIG. 1.

FIG. 6 is a fourth side view of the access-resistant jar of FIG. 1.

FIG. 7 is a top view of the access-resistant jar of FIG. 1.

FIG. 8 is a bottom view of the access-resistant jar of FIG. 1.

FIG. 9 is a cross-sectional view of the access-resistant jar of FIG. 3.

FIG. 10 is a top perspective view of an access-resistant jar in an open condition in accordance with the present teachings.

FIG. 11 is a bottom perspective view of the access-resistant jar of FIG. 10.

FIG. 12 is a first side view of the access-resistant jar of FIG. 10.

FIG. 13 is a second side view of the access-resistant jar of FIG. 10.

FIG. 14 is a third side view of the access-resistant jar of FIG. 10.

FIG. 15 is a fourth side view of the access-resistant jar of FIG. 10.

FIG. 16 is a top view of the access-resistant jar of FIG. 10.

FIG. 17 is a bottom view of the access-resistant jar of FIG. 10; and,

FIG. 18 is a cross-sectional view of the access-resistant jar of FIG. 12.

The broken lines in the drawings illustrate the portions of the access-resistant jar that form no part of the claim.
